United States Patent Office

Des. 190,489
Patented June 6, 1961

190,489

CAN OPENER

Robert J. Scott, Blue Springs, and William A. Chappell and Joseph L. Grant, Raytown, Mo., assignors to John C. Hockery, Kansas City, Mo., trustee for Henry J. Talge and Foster L. Talge, Kansas City, Mo.

Filed June 15, 1960, Ser. No. 61,049

Term of patent 14 years

(Cl. D22—2)

FIG. 1 is a front elevational view of a can opener embodying our new design;

FIG. 2 is a side elevational view of same;

FIG. 3 is a rear elevational view of same; and

FIG. 4 is a top plan view of same.

The side opposite to that shown in FIG. 2 is substantially identical therewith except that the handle portion is not present.

We claim:

The ornamental design for a can opener, as shown and described.
